UNITED STATES PATENT OFFICE.

OSCAR A. ALBRECHT, OF OMAHA, NEBRASKA, ASSIGNOR TO O. A. ALBRECHT COMPANY, A CORPORATION, OF OMAHA, NEBRASKA.

LACING-STRIP.

SPECIFICATION forming part of Letters Patent No. 695,862, dated March 11, 1902.

Application filed May 18, 1901. Serial No. 60,904. (No specimens.)

To all whom it may concern:

Be it known that I, OSCAR A. ALBRECHT, a citizen of the United States, residing at Omaha, in the county of Douglas and State of Nebraska, have invented new and useful Improvements in Lacing-Strips for Shoes, of which the following is a specification.

This invention relates to improvements in tipped lacing-strips and the method of producing the same.

The object of the present invention is the provision of a tipped lacing-strip designed for lacing shoes and other similar purposes, and one which is of such form as to materially reduce the cost of manufacturing the same; and, furthermore, the invention aims to provide a shoe-lace tip which is so formed as to be sufficiently hard for the purposes for which the same is designed as to be unaffected by wear, but sufficiently flexible or elastic to prevent breakage.

A further object of the invention is to provide an improved process for manufacturing tips on lacing-strips so that the cost of producing the same will be materially lessened.

With these and other objects in view, which will appear as the nature of the improvements is better understood, the invention consists, substantially, in the novel form of tipped lacing-strip and the process of producing the same, as will be hereinafter fully described, illustrated in the accompanying drawings, and pointed out in the appended claims.

In the drawings, Figure 1 is a top plan view of the fabric from which the herein-described tipped lacing-strip is formed. Fig. 2 is a similar view of the fabric in the first step of the process. Fig. 3 is a view in elevation, illustrating the fabric shown in Fig. 2 after being compressed. Fig. 4 is a similar view to Fig. 3, illustrating the fabric severed and the strips complete.

Referring to the drawings, the numeral 1 designates a suitable fabric from which the herein-described lacing is formed, said fabric being of the ordinary woven material, and it will be here noted that after the fabric has been treated by the herein-described process the same forms two complete lacing-strips. It will also be observed, however, that the fabric may be of considerable length and treated

at different points throughout its length, according to the length of each strip, and when severed the fabric of such length constitutes a series of lacing-strips. This, however, is 55 determined by the manufacturer.

To form the herein-described strip, the fabric is treated at a suitable point to a covering of powdered shellac 2 or any other gum which may be deemed desirable. The shellac 60 or other gum is powdered and sifted over the portion of the fabric 1 to be treated, and after this has been done the fabric is pressed between two heated dies, whereby the shellac is melted and the fabric saturated therewith. 65 After the fabric has been removed from the heated dies the saturated portion becomes hard, but brittle, and after this hardening of the shellac the fabric is next treated with boiled linseed-oil. This treatment may be effected 70 by passing the fabric between two felt pads containing the oil, whence the fabric passes into a second set of dies, which are heated to such a degree as to effect softening of the shellac. In this latter step the treated 75 portion of the fabric is compressed and shaped to form the tips of the strips, as shown at 3 in Fig. 3. The linseed-oil used as above described serves two purposes—to wit, it primarily prevents the shellac or other gum from 80 sticking to the dies, and, secondarily, but of greater importance, the shellac absorbs the oil, or, in other words, the dies effect an admixture of the oil and the shellac. As the formed tips pass from the dies the same have 85 a smooth surface, but are hard and elastic, and in order to complete the tips it is necessary to japan the same or otherwise finish the tips according to the desires of the manufacturer. This finishing is preferably effected 90 by immersing or covering the tips in dissolved celluloid; but it is obvious that any other form of finishing may be used. After finishing the tips the fabric is severed, as shown in Fig. 4, after which step the strip is 95 in its completed state.

Having thus fully described my invention, what I claim as new, and desire to secure by Letters Patent, is—

1. The herein-described process of tipping 100 a lacing, which consists in applying powdered gum to a strip of woven material, pressing

and heating same, treating it with oil, and heating, compressing and shaping the same to form a tip.

2. The herein-described process of tipping a lacing, which consists in applying powdered gum to a strip of woven material, pressing and heating same, treating it with oil, and finishing the strip by coating the same.

3. The herein-described process of tipping a lacing, which consists in applying powdered gum to a strip of woven material, pressing between pads containing oil, and heating, compressing and shaping the same to form a tip.

4. The method of making tips on lacers, which consists in applying a fusible gum to a portion of the lacing, then simultaneously heating and pressing the gummed portion to incorporate the gum in the lacing, then ap-

plying oil to the gummed portion, and then simultaneously heating, and compressing the lacing to form the tips.

5. The method of making tips on lacings, which consists in applying a fusible gum to a portion of the lacing, then simultaneously heating and pressing the gummed portion to incorporate the gum in the lacing, then applying oil to the gummed portion and then simultaneously heating and compressing the lacing to form the tips, and then coating the tips.

In testimony whereof I affix my signature in presence of two witnesses.

OSCAR A. ALBRECHT.
